UNITED STATES PATENT OFFICE

WILLIAM A. STABENOW, OF SALEM, OREGON

HARROW

Application filed May 10, 1929. Serial No. 361,991.

This invention relates to harrows, or what might be called a pulverizer.

The object of my invention is the construction of a simple and efficient apparatus for harrowing or pulverizing the soil.

Another object of the invention is the construction of an efficient and novel means for supporting the shaft, carrying discs, in a harrow.

10 A still further object of the invention is the construction of a novel and efficient lever device whereby the disc and spring teeth of a harrow may be operated for lowering or raising the same, during the operation of the apparatus.

With the foregoing and other objects in view, my invention comprises certain novel constructions, combinations and arrangements of parts as will be hereinafter fully described, illustrated in the accompanying drawings, and more particularly pointed out in the appended claims.

In the drawings:

Figure 1 is a view in side elevation of an apparatus constructed in accordance with the present invention, while

Figure 2 is a top plan view of the same.

Figure 3 is an enlarged fragmentary, perspective view of the apparatus, showing particularly the lever device therefor.

Figure 4 is an enlarged fragmentary, perspective view of the apparatus, showing a modified form thereof.

Figure 5 is an enlarged sectional view, taken on line 5-5, Figure 1.

Referring to the drawings by numerals, 1 designates the main or primary frame, which is L-shape in cross section (see Figs. 4 and 5).

40 A front, inverted U-shape or auxiliary frame 2 and a rear, inverted auxiliary frame 3 are fastened at their lower ends within frame 1 by means of bolts 4 (Fig. 5). This produces a very stable connection because the lower ends of the auxiliary frames 2 and 3

45 rest upon the horizontal portion of frame 1 with part of the frames tightly held against the inner face of the vertical portion of the main frame (Fig. 5). A primary, longitudinally extending, connecting bar 5 is fastened

50 to the top of the auxiliary frames 2 and 3.

This bar 5 supports the lever device 6 hereinafter specifically described.

The front disc carrying shaft 7 is mounted in sectional journal boxes 8 carried by the pivotally mounted spring bracket arms 9. 55 Each bracket arm 9 is provided with an outer folded end 10 through which bolt 11 extends; bolt 11 is placed in one of several horizontal apertures 12, for adjustably supporting the bracket arms upon the side of the front auxiliary frame 2. Each bracket arm is twisted at 13 to produce a horizontal outer end, to which a sectional box 8 is fastened. The folded outer end 10 is sufficiently large to allow a play at 14, so that the bracket arms 60 can be pivoted through the medium of lever device 6, for placing the discs 15 close to or further away from the ground, as desired, these discs being suitably mounted upon shaft 7. 70

Shaft 7 is provided with a spline 16 (Fig. 3) engaged by hub 17 of arm 18; arm 18 is held in a fixed position, against longitudinal movement on shaft 7 by set-screw 19. The lever device 6 comprises a straight body 20 75 provided with an integral right angularly extending foot 21 to which the outer end of arm 18 is pivotally connected at 22. At 23, the body 20 of the lever device is pivotally mounted on the primary connecting bar 5. 80 A ratchet plate 24 is fastened to the bar 5 and is engaged by the ratchet device 25 carried by the lower portion of arm 26 of the lever device. This arm 26 extends at right angles to body 20, so that a greater leverage 85 can be exerted thereon by the operator for swinging arm 18 and thus raising or lowering disc 15 a greater distance for efficient operation.

In Figure 4, the embodiment is similar to that shown in Figure 1, with the exception that each of the front bracket arms 9 has on its outer end an upwardly extending portion 27 terminating in an inwardly extending, integral bearing portion 28 on which shaft 7 rests. The upper section 29 covers the shaft and is suitably fastened to the bearing portion 28, making a very efficient structure because the portion 28 can not be lost from the bracket arm; it is easily 100.

formed, and gives a springy action for overcoming, to a great extent, shocks on the discs 15, such as striking against roots and rocks in the field. In other words, I have provided a 5 springy bracket arm structure, supporting a disc carrying shaft 7.

The rear disc carrying shaft 30 is mounted on sectional bearing or journal boxes 8 supported and fastened to spring bracket arms 31. These arms 31 are similarly constructed to the front bracket arms 9, but their U-shape or overlapped inner ends are brought close to the inverted frame 3, as shown in Figs. 1 and 2, eliminating any play, 10 thereby holding shaft 30 from any vertical movement; the operator, however, can adjust the height of shaft 30 with its disc 15, by placing the fastening bolts 32 in any of the apertures 33 on frame 3 (Fig. 1).

20 Brackets 34 are fastened upon frame 1 and in the upper ends of these brackets are journalled shafts 35. Shafts 35 have spring teeth 36 fastened thereto. The teeth on the shaft nearest to discs 15 on shaft 7 are arranged in 25 alternating positions; in other words, there is only one spring tooth for every other disc on shaft 7, but the spring teeth 36 on the rear shaft on brackets 34 fill in the space between the teeth on the front shaft 35, so that 30 the two shafts 35 have spring teeth equal in number to the discs 15 on shaft 7. Extending from shafts 35 are adjustable arms 37; these arms are held in a fixed position on shafts 35 by set-screws 38. The upper ends of the arms 35 are pivotally connected by auxiliary connecting bar 39. The front end of bar 39 is adjustably connected to the body 20 of the lever device, whereby when the lever device is swung upon its pivot 23, the spring teeth 36 will be adjusted the same as the teeth 15 carried by shaft 7, for placing them closer to or further away from the ground.

In place of the discs 15 on rear shaft 30, I may substitute a packer or corrugated roller or any ordinary structure (not shown).

45 I provide, at the front end of frame 1, a suitable hitch 40, whereby draft animals or a tractor may be attached to my apparatus, for conveying the same over the ground.

50 While I have described the preferred embodiment of my invention and illustrated the same in the accompanying drawings, certain minor changes or alterations may occur to one skilled in the art to which this invention relates, during the extensive manufacture of the same, and I, therefore, reserve the right to make such alterations or changes as shall fairly fall within the scope of the appended claims.

60 What I claim is:

1. In an apparatus of the class described, the combination with a frame, of auxiliary frames on said first mentioned frame, a connecting bar on said auxiliary frames, bracket arms pivotally mounted on one of said

auxiliary frames, journal boxes on said bracket arms, a shaft journalled in said boxes, discs on said shaft, a lever device on said connecting bar, and means connecting said shaft and lever device whereby when the lever device is operated, the bracket arms, shaft and discs will be raised or lowered. 70

2. In an apparatus of the class described, the combination of a frame L-shape in cross section, auxiliary frames within said first-mentioned frame and bearing at their ends against portions of the first-mentioned frame, pivotally mounted brackets on one of said auxiliary frames, a disc carrying shaft supported upon said brackets, and lever means for raising and lowering said brackets and disc carrying shaft. 75

3. In an apparatus of the class described, the combination with a horizontal primary frame, of inverted U-shape frames on said primary frame, a longitudinally extending connecting bar fastened to said U-shape frames, said U-shape frames provided with a plurality of apertures in their sides, bracket arms engaging said U-shape frame, means extending through some of said apertures and said bracket arms for adjustably mounting the same upon said frames, a disc carrying shaft supported upon said bracket arms, and lever means carried by said primary frame and connected to said disc carrying shaft for raising and lowering the same. 85

4. In an apparatus of the class described, the combination with a main frame, of auxiliary frames on said main frame, pivotally mounted bracket arms on one of said auxiliary frames and fixedly secured bracket arms upon the other auxiliary frame, rotatable soil or ground engaging elements on said bracket arms, and means carried by the main frame and connected to said pivotally mounted bracket arms for pivoting the same upon their frame for adjusting said rotatable soil engaging element of the pivotally mounted bracket arms. 100

5. In an apparatus of the class described, the combination with a main frame, of an inverted U-shape frame fastened to said main frame, a pair of bracket arms against said U-shape frame, each bracket arm provided with a U-shape or overlapping inner end against said U-shape frame with sufficient play to allow the bracket arm to pivot upon the U-shape frame, said bracket arm being 115 twisted intermediate its length providing an outer horizontal portion, a disc carrying shaft supported upon the outer horizontal portions of said bracket arms, and lever means carried by said main frame and connected to said disc carrying shaft for swinging said bracket arms upon the U-shape frame and thereby raising and lowering the discs of said shaft. 120

6. In an apparatus of the class described, 130

the combination with a main frame, of an auxiliary frame on said main frame, a plurality of bracket arms pivotally mounted on said auxiliary frame, each bracket arm provided at its outer end with an upwardly extending portion, said upwardly extending portion provided with an integral, inwardly extending, horizontal bearing portion, a disc carrying shaft resting on said horizontal bearing portion, an upper section over said shaft and fastened to said horizontal bearing portion, and a lever device supported upon said main frame and operably connected to said disc carrying shaft.

10 7. In an apparatus of the class described, the combination with a main frame, of an auxiliary frame on said main frame, adjustable spring bracket arms pivotally mounted on said auxiliary frame, journal boxes fastened to the outer ends of said arms, a disc carrying shaft in said boxes, an arm splined upon said shaft, and lever means connected to said last-mentioned arm for raising and lowering said spring arms and said shaft.

20 8. In an apparatus of the class described, the combination with a main frame, of up-standing frames on said main frame, rear-wardly extending bracket arms on said up-standing frames, disc or rotatable element 30 carrying shafts on the outer ends of said bracket arms, and means for vertically adjusting one of said shafts.

25 9. In an apparatus of the class described, the combination with a main frame, of an auxiliary frame on said main frame, pivotally mounted brackets on said auxiliary frame, a supporting bar on said auxiliary frame, a disc carrying shaft on said pivotally mounted brackets, an arm extending 40 from said disc carrying shaft, a lever supported upon said supporting bar and comprising a straight body with a right angled foot, said foot pivotally connected to said arm, said lever provided with a right angled 45 upper portion parallel with said foot, and means for holding said lever in an adjusted position upon said supporting bar.

15 In testimony whereof I hereunto affix my signature.

50 WILLIAM A. STABENOW.
